UNITED STATES PATENT OFFICE.

ROLF J. ROLFSON, OF SAN FRANCISCO, CALIFORNIA, ASSIGNOR TO THE UNION GAS ENGINE COMPANY, OF SAME PLACE.

CARBURETOR.

SPECIFICATION forming part of Letters Patent No. 498,447, dated May 30, 1893.

Application filed December 22, 1892. Serial No. 456,050. (No model.)

To all whom it may concern:

Be it known that I, ROLF J. ROLFSON, a citizen of the United States, residing at San Francisco, in the county of San Francisco and State of California, have invented certain new and useful Improvements in Carburetors; and I do hereby declare the following to be a full, clear, and exact description of said invention, such as will enable others skilled in the art to 50 which it most nearly appertains to make, use, and practice the same.

This invention relates to a certain new and useful carburetor for attachment to gas engines, which consists in the arrangement of 55 parts and details of construction as will be hereinafter more fully set forth in the drawings, described and pointed out in the specification.

The main object of my invention is to provide a device which shall be secured direct to the engine itself and form a part thereof, for the purpose of vaporizing the volatile oil fed therein, for the running of the engine, and in this manner permit the users of gas engines to dispense with the necessity of making employment of the well known carburetors for the generation of the explosive compound for the engine, the use of which carburetors being open to the serious objection 70 that owing to the quantity of volatile liquid necessarily contained therein for generation of the explosive gas, great danger is liable to follow a back explosion from the engine.

A further object of my invention is to provide a device which, when the speed of the engine is increased or decreased, will automatically control the supply of explosive gas to the engine and that of the volatile oil from the reservoir to the carburetor, and to close 75 the supply passage for the volatile oil in case of a back explosion from the engine occurring, in order to prevent the ignition of oil contained within the reservoir, which would follow in case no automatic check were provided 80 for the supply pipe.

Referring to the drawings forming a part of this application, wherein similar letters of reference are used to denote corresponding parts throughout the entire specification and 85 several views—

Figure 1, is a side elevation of a gas engine, showing my attachment secured thereto; Fig. 2, an enlarged vertical sectional view of the carburetor; Fig. 3, detail side elevation of the carburetor; and Fig. 4, cross sectional top 55 plan view, taken on line $x-x$, Fig. 2.

The letter A, indicates an ordinary gas engine, provided with the usual exhaust pipe A', for outlet of hot products of combustion and inlet pipe A², for admission of explosive 60 gas to the engine, while B, is the operating rod for controlling exhaust valve, which is raised and lowered through the medium of any suitable cam secured upon shaft B'. These parts being well known in the making 65 and working of all gas engines call for no specific description, more especially as they form no portion of my present invention.

The carburetor consists of the casing C, which is preferably constructed of glass, open 70 at both ends, which is closed by means of metallic top and bottom plates C', C², each of which has a circular seat a, cut in the face thereof and into which ends of casing C, fit as shown, and the two plates are secured together and casing forced to snugly fit within seat a, by means of screw bolts D. The bottom plate C², is cast with two downwardly extending pipes D', D², which pipes join at their bottom and terminate in the outwardly projecting pipe D³. The pipes D', D², serve to 75 convey the explosive gas from the vaporizing chamber E, as generated therein as hereinafter set forth, to pipe D³, from whence it is fed to the combustion chamber of the engine 80 through the medium of inlet pipe A², which is connected to outlet pipe D³, as shown. The pipes D', D², are connected at their top by means of bridge E', which is provided with the central air passageway E², which is intersected by means of air inlet or supply pipe E³. This pipe may be cast integral with bottom plate or be formed separate. When formed integral it may be said to constitute a continuation of the hollow bridge, or the 85 bridge may be cast separate from the bottom plate and made in the form of a pipe. I prefer, owing to cheapness, to cast the parts integral. Into the upper end of hollow bridge or pipe E', which extends through bottom 90 plate

plate, as shown, is secured lower end of shell E⁴, which extends upwardly within the vaporizing chamber E. This shell is surrounded by a loose sleeve F, Fig. 2, which supports a 5 perforated screen e. In the device shown I make employment of a set of three screens e, e', e², the screen e', being separated from screen e, by washer d, and screen e', from e², by washer d', while the upper or top screen 10 e², is held in place and united to shell E⁴, by means of collar d². This collar is soldered or otherwise secured to the shell and thus prevents the disarrangement of the screens during handling of the device.

15 Into and through the bottom of hollow connecting bridge E', is secured a downwardly extending sleeve F', which sleeve is internally screw threaded and into which is fastened an upwardly projecting hollow guide 20 F², which guide extends within shell E⁴, as shown in Fig. 2. Through this guide works valve stem f, the upper end of which is connected to a dome-shaped valve F³, which closes the hollow shell E⁴. The lower end of the 25 valve stem is screwed into seat f', formed in sleeve f², which is located within passage way for the explosive gas, and projects through opening formed in pipe wall f³. The lower end of said sleeve is provided with an enlarged head g, which closes the air vent g', which extends through wall g³. The admission of air through this vent is controlled by 30 means of slide G.

Upon the lower screw-threaded portion of 35 the valve stem f, is secured the regulating collar G', which by being adjusted up or down on the screw-threaded lower portion of the valve stem, serves to regulate the lift of the dome-shaped valve and the inlet of volatile 40 oil within the carburetor, as hereinafter will more fully appear.

The top plate C', of the carburetor, is provided with a central opening h, which is surrounded by an annular internally screw-threaded flange H. Into this flange is fitted 45 an externally screw-threaded hollow plug H', which is closed at its lower end, and through the lower end is drilled a tapering opening h'. Within the hollow portion of the plug, is 50 fitted a tapering valve H² which moves up and down through the opening h', the taper of which corresponds with that of the valve. The taper or inclination of this valve, and valve opening, is cut to a mathematical scale, 55 so that as the valve is raised, by the lift of the dome-shaped valve, only such a quantity of volatile oil is permitted to flow through opening h', as will serve to generate a certain power, that is to say, that if the lift of the 60 dome-shaped valve is regulated so as to raise a one-half distance the lift of the valve H², will correspond therewith, consequently the passage-way of opening will likewise be limited and the quantity of oil which flows there- 65 through will be reduced. The hollow portion of plug H', has secured therein, above the ex-

treme lift of the valve, a central perforated collar H³, which prevents the valve moving beyond a certain distance. In case of a back explosion the valve H², will be forced upward until the top thereof bears against the central opening of the collar and closes or cuts off the oil passage, consequently preventing ignition of the inflammable oil.

The plug H', is formed with an enlarged 75 hollow head h³ and within the hollow portion is located a screen I, which is held in proper position by means of a screw-threaded cap I'. This cap is formed with a central opening, and the upper end of the cap is reduced so 80 as to permit supply pipe I², fitting thereover. This pipe may be of rubber or any other suitable material, and serves the purpose of conveying the volatile oil from the reservoir, which may be located at any convenient 85 point, not shown, to the oil passage.

The exhaust pipe A', of the engine is partly 90 enlarged into the casing I³, and into same extends the fresh air pipe J, which circulates therein and passes therefrom downwardly 95 and connects with inlet pipe E³. As the fresh air enters this pipe, it circulates within the same and is heated by the raised temperature of the casing, caused by the hot products of combustion from the engine being retained 100 therein, and when discharged into pipe E³, is extremely hot. This hot air passes into the hollow bridge or pipe and from there enters the hollow shell E⁴, and the suction from the engine, through pipes A², D³, D², and D' causes 105 the hot air to raise the dome-shaped valve in order to admit the hot air into the vaporizing chamber. As the hot air strikes the under face of the valve, the surface of same is raised to an extreme degree of heat, and as same is 110 lifted it contacts with lower end of valve H², and raises same so as to permit the escape of oil through passage way h', which as it escapes into vaporizing chamber falls upon the heated surface of the dome-shaped valve, the 115 heat of which and the retained hot air causes the oil to vaporize. As the carbureted air makes its escape from said chamber into pipes D', and D², it passes through the openings of the heated screens e, e', e², which not only 120 serve to extract all moistures therefrom, but also effect the separation of any and all particles. The dome-shaped valve is forced down upon its seat through the medium of the spring j, which surrounds the valve stem sleeve f², 125 which spring is compressed during the uplift of the valve. This sleeve is raised or lowered so as to open or close the air vent g'.

The outer face of sleeve F', is provided with 130 worm threads j', and upon same works the worm collar J'. This collar is provided with an outwardly extending handle J². As this handle is turned to either the right or left, the worm collar is caused to move up or down, and as thus moved serves to lengthen or shorten 135 the lift of the valve stem, owing to the fact that regulating collar contacts therewith. By

connecting the handle J^2 , with the engine governor, the same may be thrown in or out automatically by the increased or decreased speed of the engine. In case the gas flowing from the vaporizing chamber does not contain sufficient oxygen, the same may be supplied thereto by opening the vent slide G .

5 I do not confine myself to the exact details of construction shown in the drawings as many minor changes may be made therein without departing from the invention.

Having thus described my invention, what I claim as new, and desire to secure protection in by Letters Patent of the United States, is—

- 5 1. In a carburetor, the combination with the carbureting chamber, of a tapered guide passage for the volatile oil leading into said chamber, a tapered valve mounted in said guide passage and held therein by gravity, an air inlet, an exit for the carbureted air, and a valve controlling the flow through the air inlet and constructed to actuate the valve in the guide passage and thereby regulate the supply of volatile oil.
- 5 2. In a carburetor, the combination with the carbureting chamber, of a hollow plug secured in the top of the same and having a downwardly tapered opening in its lower end and a tapered valve mounted loosely in the plug and resting normally in said opening.

3. In a carburetor, the combination with the carbureting chamber provided with an oil inlet and an outlet for the explosive gas, of an air inletshell or tube arranged within the said chamber, a valve to open and close said shell, a valve stem guide, a stem secured to the valve and extending through the said guide, and a spring acting on said stem to close the valve.

4. In a carburetor, the combination with the carbureting chamber provided with an oil inlet and an outlet for the explosive gas, of an air inlet, a valve to open and close the air inlet, a valve stem guide, a stem secured to the valve and extending through the said guide,

and a stop adjustably secured on the stem and 45 adapted to impinge against the guide and thereby limit the movement of the valve.

5. In a carburetor, the combination with the carbureting chamber having oil and air inlets, of an outlet pipe for the explosive gas, 50 an air vent in said outlet pipe, a slide on the outer side of said vent, a valve for the air inlet, and a valve on the inner side of said vent connected with the valve for the air inlet.

6. The combination with the carbureting 55 chamber, of a hollow plug extending through the top of the same and having a tapered opening in its lower end, a valve resting normally in said opening, and a centrally perforated collar secured in the plug above the 60 valve and constructed to limit the movement of the same.

7. The combination with the carbureting chamber, of a hollow plug extending into the top of the same, a valve located within the 65 plug, a screen arranged transversely within the plug, a cap secured to the end of the plug and bearing on the screen to hold the same in place, and a perforated collar within the plug acting as a stop for the valve.

8. In a carburetor, the combination with the carbureting chamber having oil and air inlets and a gas outlet, of a valve in the oil inlet, a valve in the air inlet constructed to operate the oil inlet valve, a valve stem depending from the air inlet valve, a guide through which said stem passes, an adjustable collar supported by the lower end of the guide, means for adjusting said collar, and a stop on the valve stem constructed to impinge against said 80 collar.

In testimony whereof I affix my signature in presence of two witnesses.

ROLF J. ROLFSON.
